UNITED STATES PATENT OFFICE.

THORSTEN VON ZWEIGBERGK, OF CLEVELAND, OHIO, ASSIGNOR TO THE WESTINGHOUSE ELECTRIC AND MANUFACTURING COMPANY, OF PITTSBURG, PENNSYLVANIA.

CONTROLLER.

SPECIFICATION forming part of Letters Patent No. 643,442, dated February 13, 1900.

Application filed March 31, 1899. Serial No. 711,249. (No model.)

To all whom it may concern:

Be it known that I, THORSTEN VON ZWEIGBERGK, a subject of the King of Sweden and Norway, residing at Cleveland, in the county 5 of Cuyahoga and State of Ohio, have invented a certain new and useful Improvement in Controllers, of which the following is a full, clear, and exact description, reference being had to the accompanying drawings.

10 My invention relates to controllers primarily adapted for railway-motors. One of its objects is to provide a simple and efficient emergency-brake. This is accomplished by giving the main controller a position where the motors shall be closed upon themselves, so that the simple reversing by the reversing-switch shall cause the motors to form an electric brake.

Other parts of the invention are concerned 20 in a magnetic blow-out, in the construction of the reversing-switch, in a magnetic lock preventing the operation of the reversing-switch under certain conditions, and in a simple form of cutting-out contact-finger.

25 The invention may thus be best summarized as consisting of the combinations of the parts hereinafter described, and set out in the claims.

In the drawings which clearly disclose my 30 invention, Figure 1 is a front elevation of a controller with the usual covering removed. Fig. 2 is the said elevation, partly sectional, of the reversing-switch and its coöperating parts, the contact-fingers being omitted. Figs. 35 3, 4, and 5 are horizontal sections on the lines 3, 3, 4, 4, and 5, 5, respectively, in Fig. 1. Fig. 6 is a horizontal section through the blow-out, being on the line 6, 6 on Fig. 1. Figs. 7 and 40 8 are respectively a plan, partly sectional, of the cut-outs and a perspective view of one of the cut-out levers. Fig. 9 is a developmental diagram of the controller and its connections.

Referring to the parts by letters, D represents a suitable frame which carries bearings 45 d d', in which the shaft of the main or governing cylinder E is journaled. On this shaft are the contact-segments e' to e¹⁴, which are separated from the shaft by an insulating-sleeve e²¹ and are divided into groups by the 50 insulating-collars e²². Thus the plates e' to e⁹ are all electrically connected together. Like-

wise the plates e¹⁰, e¹¹, and e¹² and the plates e¹³ and e¹⁴ are electrically connected together and both connected to the ground. These plates engage with contact-fingers, (designated K,) which receive the terminals from the resistance and reversing switch, as illustrated in the diagram. 55

The controller is of the series-parallel type, and its electrical operation for the series and parallel positions will be readily understood from the diagram, where T represents the line from the trolley; q, the line to the blow-out Q; R' to R³, the line from the resistance; A', A², F', and F², the armatures and fields of the 60 two motors; B, C, and C', lines to the reversing-switch; f' and f, lines from the first motor; L' L³, lines to the magnetic lock through the resistances R⁴ and R⁵, and G the ground. 65

The controller carries plates, (designated e¹² 70 and e¹⁴), which at the off position are engaged by contact-fingers connected so as to thereby close the motors upon themselves. Thus the line f', coming from the field of the first motor, is connected by the plate e¹² with the line 75 L', which leads through a magnetic lock to the line B to the other side of the armature of the first motor, and the line f² from the field of the second motor, being connected with the ground, the plate e¹⁴ connects the 80 line C from the other side of the armature of this motor with the ground from the magnetic lock. This closing of the motors upon themselves whenever the governing-controller is turned off is normally inoperative—that is, 85 no braking action is produced, since the momentum of the car revolves the motors in the same direction as their own current would revolve them. If, now, while the car is still moving by momentum or gravity the reversing-switch is thrown, the motors become active generators, causing a current in the opposite direction, and this blocks the motors, tending to stop them. Thus a very simple emergency-brake is provided, as after the current is thrown off all that is necessary is to 90 throw the reversing-switch. 95

On the upper end of the main controller-cylinder is a detent-wheel J, having peripheral notches, into which takes a roller carried by the arm j and drawn toward the detent-wheel by an adjustable spring j'. 100

The reversing-switch includes a wooden body N, of the mutilated cylindrical shape shown, and contact-segments n' to n^6 , secured to the cylindrical surface therof. The alternate segments n^3 and n^5 and the segments n^4 and n^6 are extended on the flat sides of the body and connected together by integral vertical metallic strips n^7 and n^8 , set into those flat sides.

Secured to the lower end of the body N by wood-screws is a socket-plate N', into which projects a pivot-pin N², carried by a bracket N³, extending from the wooden block N⁴, which carries the contact-fingers. At the upper end the wooden body extends into a socket N⁹ on the lower end of the sleeve N⁵, screws N⁶ passing diagonally through the laterally-extending wall N¹⁰ of the socket into the wooden body. Near its upper end this sleeve N⁵ has formed integrally with it the notched detent-plate N⁷. With this plate engages a roller m, carried by a lever M and pressed toward the detent-plate by a spring m². A shaft N⁸, on the upper end of which the reversing-lever takes, stands within the sleeve N⁵ and is rigidly secured to it. The construction just described reduces the cost of making the reversing-switch, and by having the reversing-switch body made of a solid piece of wood instead of around the shaft it is much reduced in size.

The reversing-switch engages with two sets of contact-fingers K' and K², either row of plates n' and n^2 or n^3 to n^6 engaging with either set of fingers, one position thus connecting the motors "ahead" and the other "reverse." The electrical connections from these fingers will be apparent from the diagram.

From the connections shown in the diagram it will be seen that if either motor burns out it may be cut out simply by disconnecting at the reversing-switch the line B or C, which leads from the main controller for this motor, and operating the controller on the parallel position, the line being simply open on the series. This disconnection I cause by withdrawing either of the upper contact-fingers from the path of the switch. These fingers normally bear against the flattened surface of the bar k, lying in the groove k' in the projecting arm k² of the bracket k³, which carries the contact-finger. The ends of this bar are secured to the forked arm k⁴, through the opening of which extends the contact-finger. The arm k⁴ normally stands about parallel with the bracket k³; but it may be turned forward into the position shown in full lines at the right in Fig. 7. In this movement the bar constitutes an eccentric and forces the contact-finger out of the path of the segment, the resilience of the finger keeping the bar and arm in place in either of their extreme positions.

The method of braking which the present controller provides is that of an emergency-

brake, (the motors being closed upon themselves,) it not being the intention to vary the braking force. It is desirable, however, in order to prevent too severe braking action that there shall be resistance in the brake-circuit. In order also to prevent subsequent movement of the reversing-switch after it has established the brake-circuit, which might severely burn the reversing-switch, I provide a magnetic lock which comes into action as soon as the braking-current begins to flow and locks the reversing-switch until the stoppage of the car discontinues the current. This magnetic lock consists of a magnet-core O, having the pole-piece o, (both preferably made integral with the back plate of the frame D,) the lines L' and L² wound independently around the core, and the armature-lever O', which the pole-piece is adapted to attract. This armature-lever has a tail o', which when the armature is attracted stands just behind the toe m' on the detent-lever M. Ordinarily this tail is out of the path of the detent-lever; but when the motors are closed upon themselves by the main controller being at the off position the circuit leads through this lock, and when the motors are reversed and the brake-current builds up the magnet becomes energized and the tail o' is swung upward into the path of the lever M and the reversing-switch cannot be changed in position until the car has come to a stop and the current thus dies down. The brake resistances R⁴ and R⁵ are in the same branch lines with the lock and come into action only when the brake is applied.

In order that the spark at the main contacts of the main controller shall be rendered as harmless as possible, I provide a very simple and efficient blow-out and deflector. This consists of a vertical iron bar P, pivoted axially by means of the screws p' and having projected from it the rigid iron plates p. Surrounding the bar P between the plates is a coil of wire Q, the coil winding in opposite direction between the successive plates. Thus when the current is flowing each pair of plates and the bar between them make a horseshoe-magnet, and lines of force pass across from the free poles and tend to blow out the arc formed by the segments separating from the contact-fingers. The plates P are inclosed in insulating-boxes S, having covers S', and the coils are protected by insulating-sleeves S², against which the floors of the boxes S' and the covers abut. These sleeves are flattened on their front sides, and the ends of the coils pass out to the front at the upper and lower ends of the sleeves and are connected across the edges of the boxes S, the connections being designated q' in Fig. 1 and lying in a groove in the protecting wooden strip S³, secured to the sleeves.

At the upper and lower ends of the bar P it has secured to it the fiber plates S⁴, which furnish means for locking the whole blow-

out in active position, there being hooks or hasps U, which swing over the ends S⁵ of these fiber plates.

The cover S' and the insulating-box S extend upward and downward at the front and outer sides in the form of shields S⁶. At its front this shield terminates in the block S⁷, made preferably of slate. This block has its face parallel with the tangent of the controller-segment at that point and is as near the segment as practicable, and thus as the segment retires from the contact-fingers the corner of this block extends into the arc and prevents it traveling backward on the segment and confines it to the extreme end thereof.

Having described my invention, I claim—

1. A governing-controller adapted to govern a motor and having a position where the source of supply is disconnected, means whereby such controller, when it comes into such position, directly closes upon itself a circuit in series through the armature and field of the motor, combined with a reversing-switch adapted to reverse the motor when the controller is at such position, substantially as described.

2. A governing-controller adapted to perform the two operations of governing a motor and of closing upon itself a circuit through its armature and field in series when the source of supply is disconnected, and a single operating handle or lever adapted to move the controller for these two operations, combined with a reversing-switch adapted to be moved when the controller has the circuit thus closed through the motor and thereby apply an electric brake, substantially as described.

3. The combination, with a series-wound motor, of a controller having a contact-plate which, at a position of the controller where the source of supply is cut off, closes the motor as a whole upon itself, a reversing-switch, means for locking the reversing-switch when the current is on but allowing it to reverse the motor when said contact-plate is in engagement, substantially as described.

4. The combination, with a pair of motors, of a reversing-switch and a series-parallel controller which has contact-segments which come into action at the usual off position of the controller and close the motors upon themselves, said closure being normally inoperative but allowing the brake to be applied by a reversal of the motors by the reversing-switch, substantially as described.

5. A governing-controller having an off position and a plurality of running positions on one side only thereof, means for preventing movement of the controller from the off position in the other direction, a contact-plate carried by the controller which is out of engagement at any running position but is in engagement at said off position, said contact-

plate when in engagement operating to close upon itself a series circuit through the armature and field of the motor, combined with such motor and a reversing-switch, substantially as described.

6. The combination, with a controller, a reversing-switch and a motor, of a line leading from a contact-finger at the controller to the reversing-switch, lines leading from the reversing-switch to the armature and field of the motor, a line leading from the motor to another contact-finger on the controller, and a contact-plate on the controller which comes into action at the off position and connects together said two contact-fingers and thus closes the motor upon itself, substantially as described.

7. The combination, with a controller, a reversing-switch and a motor, of a line leading from a contact-finger at the controller to the reversing-switch, lines leading from the reversing-switch to the armature and field of the motor, a line leading from the motor back to the controller, a branch line leading from the first line mentioned to a contact-finger on the controller, a contact-plate on the controller which comes into action at the off position and connects together said two contact-fingers, and thus closes the motor upon itself, and a magnetic lock in said branch line adapted to lock the reversing-switch, substantially as described.

8. The combination with a motor, and means for closing it on itself and for reversing it, whereby a braking-current is generated, of a lock which automatically comes into action when said braking-current is flowing, and prevents the subsequent reversal of the motor until the braking-current dies down, substantially as described.

9. The combination with a motor, and means for closing it on itself and a reversing-switch, of a magnetic lock in the circuit of the motor when it is thus closed upon itself, said lock being adapted to prevent the subsequent movement of the reversing-switch to open the circuit while sufficient braking-current is flowing, substantially as described.

10. A motor, a switch for reversing it, a governing-controller, a branch line leading from one side of the motor to the controller and adapted to be connected at the controller with a line from the other side of the motor, thus closing it upon itself, in combination with a magnetic lock in said branch line adapted to lock the reversing-switch, substantially as described.

11. The combination, with an electric switch having a notched detent-wheel, of a lever carrying a roller adapted to stand in the notches thereof, a magnet, a pivoted lever adapted to be moved by said magnet into the path of the detent-lever and thereby prevent the operation of the switch, substantially as described.

12. The combination, with a series-wound

motor and a resistance, of a controller which at the off position closes a series circuit through the resistance, the armature and the field of the motor, with a reversing-switch adapted to reverse the motor when the controller is in such off position, substantially as described.

13. A motor having an armature and field connected in series, a switch for reversing said armature or field, a governing-controller, a branch line leading from one side of the motor to the controller and adapted to be connected at the controller with the line from the other side of the motor, thus closing the motor as a whole upon itself, in combination with resistance in said branch line, substantially as described.

14. The combination of a governing-controller adapted to close a motor upon itself, a reversing-switch adapted to reverse said motor, said reversing-switch having a detent-plate, a detent-lever coöperating therewith, and preventing its movement unless the detent-lever is moved, a magnetic lock in circuit with the motor when it is closed upon itself, said lock operating to move a stop into the path of said detent-lever and prevent the operation of the reversing-switch when a sufficient braking-current is flowing, substantially as described.

15. The combination with a reversing-switch, a notched detent-plate carried thereby, a detent-lever having a roller engaging with said plate, a magnet-core O carried by the frame of the controller, a pole-piece carried by said core, coils around the core, a pivoted armature-lever O', one end of which is adapted to be attracted by the pole-piece, the other end being thereby brought into the path of the detent-lever, substantially as described.

16. The combination with a series-parallel controller, a reversing-switch and a pair of motors, of a magnetic lock adapted to prevent the operation of the reversing-switch, said lock having two independent windings, which are a part of branch lines leading to the two motors, and means operated by the controller for connecting such branch lines with the other side of the motors, thus closing the two motors upon themselves through the magnetic lock, substantially as described.

17. In an electric switch, in combination, an insulating-body which is a mutilated cylinder having two cylindrical surfaces and two flattened surfaces, contact-segments secured to said cylindrical surfaces, one of said sets of segments extending alternately onto said two flattened surfaces and longitudinal strips on the flattened surfaces connecting said alternate extended segments together, substantially as described.

18. An electric switch having an insulated body, an operating-shaft and a sleeve surrounding said shaft and extending over said body, and means for securing said sleeve to the body, substantially as described.

19. An electric switch having an insulated

body, an operating-shaft N⁸ axially in line with the body, a sleeve surrounding said shaft and extending over said body, and screws securing said sleeve to the body, substantially as described.

20. An electric switch having a body composed of a solid block of wood, an operating-shaft axially in line with said body, a sleeve surrounding said shaft and having a socket in which said body extends, and means for securing said body in said socket, substantially as described.

21. In an electric switch, in combination, a body of insulating material, contact-segments secured thereto, a sleeve N⁵ carrying on its end a socket which takes over said body, said socket having the laterally-extended wall N¹⁰, screws N⁶ passing diagonally through said wall into said body, and means for turning said sleeve on its axis, substantially as described.

22. In a reversing-switch, in combination, an insulating-body N carrying contact-segments, a socket-plate N' into which said body extends in the lower end and to which it is secured, a pivot-pin extending into said socket-plate, a sleeve N⁵ above the body and carrying at its lower end a socket into which the upper end of the body extends, means for securing said socket to the body, and an operating-shaft extending into and secured to said sleeve, substantially as described.

23. In an electric switch, an operating-shaft, a switch-body in axial alinement with the shaft, a sleeve surrounding said shaft and secured to it, said sleeve having at its lower end an integral socket into which the switch-body takes and at its upper end an integral detent-wheel, combined with a detent-lever carrying a roller adapted to engage said detent-wheel, substantially as described.

24. The combination with a movable switch of a contact-finger adapted to stand in the path of said switch, an eccentric bar between said finger and a rigid member, and an arm secured to said bar and adapted to turn it axially to force the finger away from the switch, substantially as described.

25. In an electric switch, in combination, a movable body carrying contact-plates, a contact-finger adapted to engage therewith, a rigid block on that side of the finger toward the body, said block having groove in it facing said finger, a flattened bar occupying said groove, an arm secured to said bar and adapted to turn it on its axis and cause it to force the finger out of the path of the switch-body, substantially as described.

26. A cut-out finger for an electric switch consisting of a contact-finger, a rigid block k² having a groove k' therein facing the finger, a flattened bar k occupying said groove, a forked arm k⁴ secured to the ends of said bar and having the contact-finger extending through it, said contact-finger contacting with said flattened bar and holding it and the forked arm in place, and said arm being adapt-

ed to be turned on its axis, to withdraw the finger from its normal position, substantially as described.

27. The combination, with a set of contact-fingers, of a pivoted bar P , a series of plates p rigid with said bar and extending between the contact-fingers, coils around said bar between the plates, insulating-sleeves S^2 surrounding said coils, insulating-boxes surrounding the edge of the plates and covering their upper and under sides and substantially contacting with said insulating-sleeves, substantially as described.

28. The combination, with a set of contact-fingers, of a pivoted bar P , a series of plates p rigid with said bar and extending between the contact-fingers, coils around said bar between the plates, insulating-sleeves S^2 surrounding said coils, insulation surrounding the edges of the plates, said sleeves being flattened on their front sides, a protecting-strip S^3 secured to said flattened sides, the consecutive coils being connected together between the insulation around the edge of the plates and the protecting-strip, substantially as described.

29. The combination, with a controller having a series of contact-segments, and contact-fingers adapted to engage therewith, of insulating-blocks S^7 supported close to the contact-segments and near the contact-fingers, said block having its corner extending into the arc caused by the separating contact plates and fingers and thus preventing the arc traveling back on the segment, substantially as described.

30. The combination, with a controller having a series of contact-segments, and contact-fingers adapted to engage therewith, of a blow-out having insulating-boxes extending between the fingers, and insulating-blocks S^7 carried by said boxes close to the contact-segments and in front of the contact-fingers, said block operating to prevent the arc traveling back on the segment as it leaves the contact-fingers, substantially as described.

In testimony whereof I hereunto affix my signature in the presence of two witnesses.

THORSTEN VON ZWEIGBERGK.
